HYDROCRACKING OF PETROLEUM RESIDUUM WITH USE OF GRAVITY BED OF CATALYTIC PARTICLES

William C. Lanning, Bartlesville, Okla., assignor to Phillips Petroleum Company, a corporation of Delaware

Application December 3, 1954, Serial No. 473,015

7 Claims. (Cl. 208—108)

This invention relates to a process for the hydrogenolysis of petroleum residues and other heavy hydrocarbons.

Gasoline is by far the most important product of the petroleum industry. The primary goal of the petroleum refiner is to produce the maximum quantity of gasoline of highest possible quality from a barrel of petroleum at the least possible cost. The most important step forward towards this goal in recent years was the introduction of catalytic cracking. This process affords good yields of gasoline of considerably improved quality and is now in wide commercial use throughout the country. It is generally difficult or impractical to effect the catalytic cracking of heavy hydrocarbon fractions, such as topped or reduced crude, or other residual fractions, because of excessive coking and contamination of the catalyst, as well as excessive production of low grade products. Usually hydrocarbon crudes or residual fractions are subjected to vacuum distillation, propane deasphalting, or other suitable processes to remove alphanolanes and coke forming constituents, whereby a relatively light gas oil is obtained for charging stock to a catalytic cracking unit.

Destructive hydrogenation of high boiling hydrocarbons is well known. Conversion of such materials can be satisfactorily accomplished in this manner, but it requires rather high pressures of the order of 3000 p.s.i. and above. There are compelling economic reasons for employing low pressures. Also, the products obtained by such high pressure treatment are usually of inferior quality. Attempts to use lower pressures, in general, have been unsatisfactory mainly due to the fact that carbon deposition is markedly increased. The hydrogenolysis process has usually been carried out in a static bed reactor but this method of operation has not proved entirely satisfactory when attempting to obtain complete conversion of high boiling hydrocarbon fractions to distillate and coke. Therefore, it is a principal object of this invention to provide an economically feasible continuous process for the complete conversion of high boiling hydrocarbons by hydrogenolysis into lower boiling products and coke at moderately low pressures. Another object is to provide a hydrogenolysis process for completely converting petroleum residues to lighter hydrocarbon fractions and coke. It is also an object of the invention to provide a process for converting heavy hydrocarbons to lighter fractions in two stages in a single reactor wherein more severe conditions favorable to converting the heavier material flowing from the first stage are maintained in the second stage. Other objects will become apparent from a consideration of the accompanying disclosure.

This invention is concerned with an improved process for the hydrogenolysis of petroleum residues to obtain complete conversion of the residue to distillate and coke in a moving bed reactor, said improvement comprising passing a preheated charge oil and an H₂-containing

2

gas downwardly concurrently with the catalyst in the top section of the reactor, introducing an H₂-containing gas at the bottom of the reactor so as to pass upwardly countercurrently to the unconverted liquid charge and catalyst in the bottom section of the reactor, withdrawing a vaporous effluent produced in both sections at some intermediate point in the reactor, removing the coke covered catalyst from the reactor, and regenerating and returning the regenerated catalyst to the reactor.

According to the invention, a hydrogenolysis process is carried out using a granular or pelleted catalyst that flows downwardly in the reactor by gravity and forms a solid moving bed of catalyst therein, coke-covered catalyst being continuously withdrawn from the reactor, regenerated, and returned to the reactor. Heated charge together with hydrogen is introduced at the top of the reactor and moves concurrently with the catalyst through the upper portion of the reactor. The vaporous products produced in the upper portion of the reactor along with a lesser amount of vaporous products produced in the lower portion of the reactor are removed at some intermediate point in the reactor. The catalyst continues moving downwardly through the lower portion of the reactor concurrently with the unconverted liquid charge against a counter-flow of heated hydrogen, which is introduced at a point in the lower portion of the reactor, preferably at the bottom. Hydrocarbon vapors are formed during the countercurrent flow and are removed at an intermediate point in the reactor with vaporous products and hydrogen initially present in the upper portion of the reactor, by stripping action of the countercurrently flowing hydrogen. The remainder of the liquid charge, not converted to vaporous products, is converted to coke and removed with the catalyst to the regenerator. Thus it can be seen that the process of the invention utilizes the catalyst very efficiently to obtain complete conversion of the residuum to distillates and coke, the more refractory residuum being converted at more severe conditions which would not be desirable in a one-stage process.

Hydrogenolysis of the unvaporized portion of the charge stock takes place in the lower section of the reactor to produce high quality distillates simultaneously with hydrogenolysis of the vaporized portion of the charge stock in the upper section of the reactor to produce gasoline and distillates. The products from both sections include the same fractions; i.e., normally gaseous hydrocarbons, gasoline, diesel oil, light and heavy gas oils, and coke. The properties of the corresponding fractions differ somewhat because of the difference in material being converted, but this, perhaps, is not significant since all products are combined. The significant difference is that the more refractory residuum is converted at the more severe conditions in the bottom section. Since the more refractory residuum is usually more aromatic, the products are also more highly aromatic or less paraffinic.

Examples of suitable feed stocks that can be treated according to the present invention include crude petroleum, reduced or topped crude, high-boiling tarry fractions, heavy gas oils, and other fractions. In general, the pressures utilized in the reactor may range from 200 p.s.i. to 1000 p.s.i., preferably from about 400 to about 700 p.s.i., with temperatures in the range of 650–950° F., preferably 800–900° F. in the upper section of the reactor and 900–1100° F., preferably 950–1050° F., in the lower reactor section. The maximum temperature in the lower section should be at least 50° and, preferably, at least 100° F. higher than that in the upper section to effect the required coking and conversion. The feed rates may vary widely, but are generally in the

range of 0.5 to 4 volumes feed per volume of catalyst per hour. The total amount of hydrogen charged to the reactor may range from about 4000 to about 15,000 cubic feet per barrel of fresh oil charged. Examples of suitable catalysts that may be used in the invention are nickel, cobalt, and iron as metals and/or oxides; nickel tungstate, cobalt molybdate, chromium, molybdenum and tungsten oxides or sulfides, etc. These catalysts are generally distributed on or otherwise composited with a porous carrier such as activated alumina, silica gel, silica-alumina cracking catalyst, etc.

More complete understanding of my invention will be obtained by reference to the accompanying diagrammatic drawing which presents a preferred arrangement of apparatus and flow in accordance with the invention.

The apparatus in which the process is carried out consists of a reactor 10 and a regenerator 11 which may be built into a single tower 12. Catalyst is fed by gravity from an upper catalyst hopper 13 by line 14 into catalyst distributing head 15 which comprises a catalyst feed tray 16. A petroleum residue charge stock in line 17, such as a reduced crude oil having an initial boiling point in the range of 700-850° F. with fresh and recycle hydrogen supplied through lines 18 and 19 is passed to preheater 20, heated to a temperature in the range of 825 to 925° F., and passed through line 21 to the top of reactor 10. The hydrocarbon feed, hydrogen, and catalyst pass concurrently downward through the reaction zone 10, the vaporous product and excess hydrogen being removed at an intermediate point in the reactor, at gas separating means 22, and passed through line 23 to a cooler 24 and high pressure separator 25. An overhead stream rich in hydrogen and containing some light hydrocarbons is removed from high pressure separator 25 through line 26 for recycle to reactor 10, or for other utilization, in part or in whole, through line 43. Also entering reactor 10 is the remaining portion of fresh and recycled hydrogen supplied through lines 18 and 27, and passed through line 28, preheated in preheater 29 to a temperature preferably in the range of 900 to 1100° F., and passed through line 30 to reactor 10, entering at a point in the lower part, preferably at the bottom. The reaction in both the upper and lower sections of the reactor is in mixed phase since both hydrocarbon vapor and unconverted liquid hydrocarbons are present. In the lower portion of the reactor the hydrocarbon and hydrogen are contacted in countercurrent flow, and in the upper portion the flow is concurrent.

The coke coated catalyst is fed by gravity through line 31 into regenerator 11. Air and inert gas or superheated steam are injected into the regenerator via line 32 whereby the coke and other deposits are burnt off the catalyst in conventional manner. Temperatures are controlled by varying the air flow and also by means, where necessary, of a cooling system (not shown) located within the regenerator. The regenerated catalyst flows by gravity from the regenerator through a seal leg 33 to a lower catalyst hopper 34. The catalyst is picked up by a stream of flue gas introduced into the hopper 34 by line 35, and lifted via lift 36 to the upper catalyst hopper 13, from which the flue gas is vented through line 37, the catalyst being fed back into the reactor. The flue gas leaving the regenerator is split into two streams, one being used as catalyst lift gas, and the remainder being vented through line 38. If desired, compressed air or a mechanical elevator can be used for elevating the regenerated catalyst to the upper catalyst hopper. Catalyst inlet temperature to the reactor is controlled by any suitable method such as by regulating the gas lift temperature.

The liquid hydrocarbon products recovered from high pressure separator 25 are passed to a fractionator 39 through line 40, wherein this fraction is separated into a low boiling range fraction comprising gasoline removed

by line 41, a diesel oil fraction by line 42, and a light and heavy gas oil fraction by line 43. The light and heavy gas oil fraction is a very desirable charge stock for catalytic cracking, and is preferably passed to such a unit to convert the gas oils to gasoline, fuel gas, heating oil, and coke.

Fresh catalyst may be introduced to the system at any suitable point in the apparatus such as in catalyst hopper 13 in conventional manner.

10 The following specific example is set forth to illustrate the invention and provide a better understanding thereof.

A Panhandle residuum having an initial B.P. of 1050 to 1100° F. and a high-sulfur Montana topped crude having an initial B.P. of about 400° F. when subjected to 15 hydrogenolysis in apparatus arranged substantially as in the drawing, utilizing a feed inlet temperature of about 850° F., a cobalt molybdate catalyst supported on alumina at an inlet temperature of about 850° F., 2 volumes of charge oil per hour per volume of catalyst, a 2-hour 20 residence time of catalyst in the top section of the reactor, 2000 cubic feet per hour of H₂ per barrel of liquid feed to each section, a hydrogen feed temperature to the lower section of 1000° F., and operating pressure of 500 p.s.i.g., yield the results shown in the table. This operation requires a flow of 0.5 barrel per hour of catalyst to the reactor, 2 barrels per hour of oil feed, and 4000 cubic feet per hour of H₂-containing gas. There is a flow of about 0.6 barrel per hour of residual liquid oil into the lower section which requires an upflow of H₂ gas of about 1200 cubic feet per hour. (Flow rates are expressed in barrels per barrel of reactor space.)

Table

	Panhandle Residuum	High-Sulfur Montana Topped Crude	Yield, Wt. Percent of Charge
C ₁	1.9		
C ₂	3.0		
C ₃	4.4		3.2
C ₄	5.1		
C ₅ -400° F.	28.2		20.1
400-600° F.	24.8		40.8
600-850° F.	25.9		32.1
Carbon	6.7		1.6
Sulfur (H ₂ S)			2.1

Thus, by the practice of the present invention, residual stocks which would otherwise have to be sold as low cost heavy fuel oil, or otherwise used as low grade heavy products, are converted to valuable catalytic cracking feed, in an economically feasible continuous process, which may be cracked over catalysts, without undue contamination or coke formation, to yield high octane gasoline and other valuable products normal to the fluid catalytic cracking operation.

Certain modifications of the invention will become apparent to those skilled in the art and the illustrative details disclosed are not to be construed as imposing unnecessary limitations on the invention.

I claim:

1. A process for converting high boiling hydrocarbons to lower boiling hydrocarbons and coke by hydrogenolysis, comprising maintaining a gravitating bed of hot solid particulate catalyst in a reaction zone; contacting said catalyst in concurrent flow in the upper section of said reaction zone with a stream of higher boiling hydrocarbon liquid and hydrogen under reaction conditions including a temperature in the range of 650 to 950° F. which convert a substantial portion of said hydrocarbons to lower boiling hydrocarbons and leave a substantial portion of unreacted liquid hydrocarbon; contacting said catalyst and unreacted liquid hydrocarbon in countercurrent flow in the lower section of said reaction zone with a hot stream

of hydrogen-containing gas under reaction conditions including a temperature in the range of 900 to 1100° F. and at least 100° F. above that maintained in said upper section so as to convert a substantial portion of said liquid hydrocarbon to lower boiling hydrocarbons and coke; and recovering a gaseous effluent from an intermediate section of said reaction zone comprising the reaction products from said upper and lower sections and free hydrogen.

2. The process of claim 1 wherein the hydrocarbon feed comprises a fraction having an initial boiling point in the range of 600-850° F.

3. The process of claim 1 including feeding 4000 to 15,000 cubic feet of hydrogen to said reaction zone per barrel of hydrocarbon feed.

4. The process of claim 1 including the steps of transferring catalyst from said lower section to a burning zone; regenerating said catalyst in said burning zone by burning the coke therefrom at a temperature above about 1000° F. but below that at which substantial deterioration of said catalyst occurs; and transferring the regenerated catalyst substantially at the temperature resulting from regeneration to the upper section of said reaction zone.

5. The process of claim 1 including the steps of recovering a normally liquid hydrocarbon fraction from said reaction products; separating said fraction into a gasoline fraction and a gas oil fraction; and catalytically cracking said gas oil fraction to hydrocarbon boiling in the gasoline range.

6. A process for converting a reduced crude oil fraction having an initial boiling point in the range of 30 700-850° F. to hydrocarbons boiling in the gasoline range, comprising heating said fraction to an elevated temperature and feeding same in liquid form together with hydrogen to the upper end of a bed of hot solid particulate catalyst gravitating thru a reaction zone, the temperature 35 of said catalyst and the feed being regulated so as to

maintain a reaction temperature in the upper section of said reaction zone in the range of 650-950° F. and effect mixed liquid and vapor phase conversion of a substantial portion of said feed to lower boiling hydrocarbons including those in the gasoline range, a remaining portion in liquid form passing to the lower section of said zone; feeding a hot stream of hydrogen-containing gas at an elevated temperature and in sufficient quantity to the lower portion of said lower section to maintain therein a reaction temperature in the range of 900 to 1100° F. and at least 100° F. higher than the temperature maintained in said upper section so as to substantially completely convert said remaining portion to lighter hydrocarbons and coke; withdrawing an effluent from an intermediate section of said zone comprising reaction products and hydrogen from both said upper and lower sections; and recovering hydrocarbons boiling in the gasoline range from said effluent.

7. The process of claim 6 including the steps of withdrawing coked catalyst from the lower end of said lower section and transferring same to a burning zone; burning coke from said catalyst at a temperature below that at which substantial deterioration of the catalyst occurs by controlling the flow rate of oxygen to the burning zone; and transferring the hot regenerated catalyst to said upper section.
